REGENERATOR AIR LIFT SYSTEM AND APPARATUS THEREFOR

Filed April 27, 1920 2 Sheets-Sheet 2

Inventor:
Edwin M. Rogers,
By his Atty, F. W. Richards

UNITED STATES PATENT OFFICE.

EDWIN M. ROGERS, OF NEW YORK, N. Y.

REGENERATOR AIR-LIFT SYSTEM AND APPARATUS THEREFOR.

Application filed April 27, 1920. Serial No. 376,977.

To all whom it may concern:

Be it known that I, EDWIN M. ROGERS, a citizen of the United States, residing in New York, in the county of New York and State of New York, have invented certain new and useful Improvements in Regenerator Air-Lift Systems and Apparatus Therefor, of which the following is a specification.

10 This invention relates to, and to improvements upon, the system and apparatus for air-lifting liquids which is set forth in my Patent No. 1,339,137, issued May 4, 1920. Wherein the compound stream, or upflowing column, is regenerated by air segregation followed by re-aeration. A principal object of the present improvements is to furnish a method of and apparatus for accomplishing the described results by an air-segregation 15 supplement by a re-aeration from the exterior of the liquid stream, and also to provide for so doing while the liquid stream has a continuous flow in its uptake path or conduit.

20 25 A further object is to furnish a system of such apparatus whereby to elevate and discharge the liquid with such a minimum loss of power, to reduce the degree of fluctuation in the operation of the apparatus, and thereby secure a high degree of steadiness in the action thereof; and to provide for the discharge of the elevated liquid in a non-aerated condition.

Additional features of improvement and 30 advantages are pointed out and explained in the course of the following description.

My present invention is in part, in the nature of an improvement in and upon the apparatus and invention disclosed in my 35 Patent No. 1,374,952, issued April 19, 1921, to which reference may be had.

In the accompanying drawings forming a part of this specification, Figure 1 is a side view of an air-circuit regenerator air-lift 40 system comprising certain of the present improvements.

Fig. 2 is a sectional side view of the regenerator in a preferred form and arrangement thereof.

50 Fig. 3 is a cross-section of the regenerator shown in Fig. 2, and is taken on line 3—3 thereof.

Figs. 4, 5, and 6, illustrate further fea-

tures, arrangements and modifications deemed to be within the purview of the present invention, and which are herein-after set forth and explained in detail.

Similar characters designate like parts in all the views.

Referring to Fig. 1 of the drawings, a lower uptake-pipe, P, and an upper uptake-pipe, P², are herein shown coupled together by a regenerator, G. Compressed air may be supplied as usual, through a pipe, 21, from a source of compressed-air, (as for instance, an air compressor X), not shown; a valve, 21', in pipe 21 may be arranged to regulate such air supply in a customary manner.

The pipes, P, P², may have different lengths and sizes according to the height-of-lift and the capacity required in any particular instance. However, in some instances, the second pipe-length, at P² (or a more extended series of them), may discharge into a second regenerator, as G² connecting a third pipe length P³.

In Fig. 1, the uptake-column is shown as being set into a shaft or well, W, filled with liquid, (this usually being water) up to the level V, which also indicates the submergence-head, in this case, measured above the nozzle F². It will be understood, of course, that the air-lift, may be supported and arranged in various ways, in accordance with known practice or local conditions.

The form of regenerator indicated at G', Fig. 1, is illustrated in detail in Figs. 2 and 3, in which the casing B is shown constructed in the lower portion thereof, with the same arrangement of details as described in my said Patent No. 1,339,137. The segregation zone Z³ is upwardly enlarging from the pipe P, which is releasably connected by flange g, to the lower flange f, of said casing B. In the present instance, however, the air-collecting chamber C forms the lower portion of an air-conduit, M, which leads up (by a diversion path for the air-stream) to an annular air-chamber, M', that constitutes, in effect, and functionally, the upper part of such air-conduits, and surrounds the centrally-disposed re-aerator F. Said member C may be integrally connected to casing B by the walls b, b', (Fig. 3), of the mid-length portion of said air-conduit, and all

these parts, in practice, may be cast in one piece, as will be evident from the drawings, to practical foundrymen.

In this construction of the regenerator, (Fig. 2), the re-aerator is shown of a tubular form, and the lower end thereof is shown as if fitted closely but removably into a bearing at M^2 , formed within the casing B; the upper end may have a flange f^2 , for holding this member F, in position; and the zone, Z^4 , may be perforated with air-communating holes of a number and size suitable for the requirements in any particular instance.

The liquid-stream on being segregated and diverted in zone Z^3 , passes into the spacer, which may nearly or partially surround chamber C, and is then guided by suitably disposed wall-surfaces, as r r' , (Fig. 2), into the open lower end f^3 of the re-aerator tube F, as will be readily understood by a comparison of the several views and the foregoing description. Thus, in the device of Fig. 2, the air-segregation is effected in a concentric manner, and is directed toward the central axial line of the apparatus, and the re-aeration is effected from the exterior of the liquid-stream; and this stream, although subjected to a lateral diversion, has a continuous flow (in a concentric zone), without any inversion of the stream of liquid in any part thereof.

The rapid spreading of the aerated column in the lower part of the regenerator, due to the upwardly-increasing cross-sectional area, as already mentioned, operates not only to slacken the upflow velocity of the liquid, but also of the velocity of the air-stream relative to the segregation zone of the apparatus. For instance, supposing that in the conduit just below the line 12 (Fig. 2), the liquid-stream is moving eight feet per second, and that the air-bubbles have there increased in size to the extent of having a slippage velocity of eight feet per second; then the bubbles would be moving upwardly sixteen feet per second; in this case, the upflow velocity of the liquid-stream and the slippage-velocity of the bubbles in said stream, are equal. If, now, the stream be slackened to two feet per second, said bubbles-velocity will be reduced to ten feet per second relative to the apparatus, but the bubbles would then have a slippage velocity four times as great as the upflow velocity of the liquid-stream. And, consequently, the rate of segregative action would be increased, or multiplied, in a proportionate ratio.

In order to secure a proper speed of the upflow, it is necessary, in practice,—as in the case of ordinary air-lifts,—to have a submergence height or head, or a “submergence-effect,” somewhat greater than required for merely balancing the total

weight of the uptake column, or total lift; but since this allowance is readily made in a well-known manner, no allowance therefor has been considered in making the accompanying drawing.

Referring to Fig. 1 of my Patent No. 1,339,137, issued May 4, 1920, the lower uptake pipe, P, is therein shown terminating abruptly within the segregation chamber, and it is evident that in such a case, the up-flowing compound column,—this being a composite stream of liquid and air,—will, on emerging from said tube, naturally “blow” and be disintegrated, so that all continuity thereof, as a stream, is lost. Thus in said instance, the arriving stream becomes discontinued, and another stream is newly-formed at the entrance to the next length, or uptake pipe, of the apparatus. These objections are avoided in the forms of apparatus herein shown,—and particularly in the apparatus illustrated in Figs. 2 and 6,—by the use of means whereby the flow is continuous in a definite and continuous path.

In the particular form of apparatus arranged as illustrated in Fig. 2, the air-stream component of the compound up-flowing column, is first diverted out of a direct path, and later returned, (but in a more subdivided form), into such path. For instance, in Fig. 2, the said air-stream on emerging (still incorporated with the liquid stream) from pipe P, is at once segregated in zone Z^3 and passed into the central conduit C, thence into the side-conduit S, and through the annular chamber M' , and perforated tube F, into the liquid-column at a position where this column is about to enter the upper conduit P^2 . Thus the two component streams,—the air-stream and the liquid-stream,—are each diverted from a central or axial path, during a period of segregation, and are then recombined into a compound column in a central path, and into an aerated liquid column, at a position beyond the position where the segregation was effected.

In this instance, (Fig. 2), the liquid-stream initial diversion occurs at Z^3 , and the reversion to central-path occurs at f^3 , whereas the diverting of the air-stream occurs at Z^3 , and the reversion thereof to central-path occurs at f^3 , slightly beyond said reversion-position of the liquid stream. Thus air-stream and liquid-stream initial diversions occur in succession, as do the said reversions thereof to a central path. The courses and relations of these stream-paths, as to the said diversions and reversions are indicated by the dash-arrow lines a , a' , of which a' indicated the course or path of the air-stream, while the course of the liquid-stream is indicated by the dash-arrow line a .

Owing to the normally rapid escape from the liquid of coalesced air-bubbles in the lower or de-aeration zone of a regenerator, the liquid is there de-aerated to such an extent that it properly may be designated as "de-aerated," since it will then retain only a small proportion of the air contained therein at the time of maximum aeration. In this connection, it should be understood that, in some instances, a portion of such contained air will or may become so absorbed, or emulsified as to follow along in the moving liquid column without being all segregated in the regenerator, but this action will normally and ordinarily occur only in a moderate degree; not materially objectionable.

When the water-level,—in the intermediate chamber,—is lowered, more air flows (in a given period) into upper pipe P^2 , and this lightens the column therein, which then, having less weight, offers less resistance to the upward flow from lower pipe P into said chamber. The latter result increases both the liquid and air delivery into the regenerator, thereby raising the water-level, which, in turn, reduces the outflow of air. Thus a fluctuation is produced, the range of which is determined by the varying weights of the upflowing columns in pipes P , P^2 . These effects (or results) are co-active, each instantly it occurs, so that the described balancing action is normally continuous and automatic within the working limits of the apparatus, and operates in an analogous manner in all the specific forms of the regenerators.

The particular manner whereby the compound stream of air and liquid is separated into the described two streams intermediate to the segregation and re-aerating zone, or means, may be described as segregation by, or into, concentric zones. For instance, in Fig. 2, the compound stream in passing through zone Z^3 upwardly to line 14, becomes segregated into a central area of air and a concentric outer area of liquid; thus the process of segregation, or disassociation, is by and in a concentric manner.

It will be evident from Fig. 2 and the foregoing description, that in the regenerator shown in said view, there are, in effect, two apparatuses, a lower one for the initial segregation, and an upper one for re-aeration, these two portions being in line and constructed as one combined apparatus. In practice, however, this combined form may be modified without a departure from the general mode of action and the principle thereof. For instance, in the further improvement illustrated in Fig. 5, the segregating part of the apparatus is shown at G^{10} , and a re-aeration apparatus, at G^{20} . For convenience of comparison, the details are mostly indicated by the same reference-

characters as in Fig. 2. Instead, however, of the stream-conduits being arranged to deliver upwardly (as already described in reference to Fig. 2), these are in the form of laterall-extended pipes R , S . The pipe S is an air-stream conduit and pipe R a liquid-stream conduit, so that the segregated streams may be transferred laterally to a more or less distant position, and there combined and conducted upwardly, the same as from the upper part of the regenerator G , in Fig. 2. This lateral offsetting of the upper pipe P^2 relative to the lower pipe P , provides for meeting special conditions which may sometimes arise.

In said arrangement, of Fig. 5, the re-aeration is effected from the exterior by air passing from chamber M' through perforations in re-aerator wall F . In the same offset arrangement, the re-aeration may be effected from the center outwardly, by substituting a form of re-aeration devices suitable therefor. For instance, the form of arrangement G^{30} , as shown in Fig. 6, may be used in place of the device G^{20} of Fig. 5, care being taken to place the device G^{30} at a proper elevation, and to have the pipes R , S , properly connected.

Instead of the extended offset arrangement, Fig. 5, a short offset may be used, of which one form is illustrated in Fig. 4. In this modification, the pipe P delivers into a separation chamber,—as in Fig. 1 of my aforesaid patent,—and two conduits are provided, one for the air-stream, and another and lower one for the liquid-stream. The latter leads to the base of pipe P^2 , while the air-conduit S enters said uptake pipe P^2 at a point higher up, and has a re-aeration nozzle or like device, in proper position for aerating the liquid entering pipe P^2 from said lower conduit R . For reducing the splashing or "blowing" which may sometimes occur in chamber M' , a perforated surge-plate L is shown extending across said chamber, but with a free passage for liquid below the same; this surge-controller may be tubular and extend around pipe P , if desired.

When the offset distance from pipe P to pipe P^2 is small, a combined receiving chamber for pipe P , and delivery channel for pipe P^2 , may be made in one casting or member, and one form of this kind is adopted for the purpose of illustration in Fig. 4. In the present instance, the liquid-conduit R is shown enclosed by the walls of such a casting, while the air-stream pipe S is represented as being inserted. Also, the pipe P^2 is shown supported in place by having the lower end thereof set in a socket in the said casting, which provides a favorable mode of support therefor, as will be evident from the drawing.

A further improvement in this form of

the apparatus of Fig. 4, is indicated by the dotted lines S' , which show how the air-pipe S may be carried down, and one end S^2 thereof extended up into the pipe P^2 , and there provided with an aerating device, as F . Also, said vertically-disposed pipe-end S^2 may be slidably fitted into the bearing therefor at j , and thus be adjustable in height, for thereby regulating the position of the aerating device F ; in this case, of course, the curved part S' of this pipe should be a flexible one, such as a rubber hose; or, one of soft metal may sometimes be found suitable.

15 Said improvements in the initial aerating of the upflowing column, are deemed to be especially desirable in regenerator air-lifts having a series of the regenerators, as shown for instance, in Fig. 1, at G^1 and G^2 . This view, (Fig. 1), illustrates a further improvement whereby the liquid may be discharged in a non-aerated condition at the top of the column, in a quiet and steady manner, and without risk of "blowing out," and the loss of power due thereto.

20 In this system, Fig. 1, the regenerators G^1 , G^2 , may be preferably such as described in connection with Fig. 2, but the forms shown in Fig. 6, may be employed in some instances, if desired, and, if suitably arranged and connected. From the apparatus in the upper position, G^3 , the re-aerator is omitted, so that this apparatus operates only as a segregator. From the air-collecting chamber, as M^3 , the segregated air may be led out by a pipe p^2 to the intake of any ordinary air-compressor of suitable capacity,—herein only symbolically indicated, at X ,—or, to some other suitable air-pressure-increasing means (not shown) appurtenant to the air-circuit. Preferably, an intermediate tank or reservoir M^4 of a considerable capacity, is also used, to prevent too great fluctuations in flow and pressures. 25 From the compressor X , the air-supply pipe 21 extends down to the initial aeration means, at F^5 , at the lower end of pipe P , similarly as indicated in Fig. 1; or extends to a position in the column where the pressure is greater than the pressure at the air-segregator G^3 .

30 If we assume a height of 150 feet for the uptake column, and the upper pipe P^3 , to be 10 feet in height, the air is then drawn out at G^3 at about 20 pounds total pressure, with an air-supply pressure at lower end K of about 90 pounds in the power-line conduit 21, (including atmosphere), so that the range of compression in the air-compressor is reduced as to the volume of air required in the compressor, and a smaller range of temperature changes is involved in the operation. These advantages are deemed to be of relatively great importance, especially 35 in cases where the air-lift installation is a

relatively permanent one. In practice, suitable air-inlet means (not shown) should be provided for supplying from atmosphere to the compressor, sufficient air to make up for any air absorbed and thus carried off by the 70 discharged liquid through pipe P^4 . An improvement for this purpose is to constitute subject-matter in a separate application.

One advantage of this system and arrangement, of Fig. 1, is that the pipe P^4 75 may be carried in a lateral direction, indicated for instance by dotted lines P^4' , so that the elevated liquid may be discharged un-aerated, at points considerably distant from the uptake column.

80 By the use of a series of the regenerators placed at frequent intervals in a single-stage air-lift column,—this being the arrangement in Fig. 1,—and by construction, or structurally-adjusting, each of those successive 85 regenerators for the column-velocity and pressure due to its position, and thus to freely pass the upflowing column with only a slight resistance while properly recomminuting the air-bubble content thereof, this 90 single-stage regenerator system has, in practice, very great advantages over the ordinary compounded or multi-stage air-lift, and can be economically operated for the single-stage elevating of water to heights unusual by 95 the air-lifting method, and with a submergence-head smaller than usual, (and also of a wider range), in proportion to the height to which the water may be lifted.

98 The pair of adjacent uptake pipes, as P , P^2 , (Figs. 1, 2), being connected by a regenerator, the latter may be said to constitute a combined regenerator and uptake-column-member, which has an upper delivery end and a lower intake or stream-receiving end. 100 The re-aerator is adjacent to said delivery end, and the air and liquid segregating means,—also sometimes designated as the "segregator,"—is in a position relatively adjacent to said intake end. After separation 105 of the air and liquid into separate streams, these are conducted to the re-aerator in opposing directions, or ways, respectively, and the stream-guiding means therefor operates also as a continuous-flow-maintaining means 110 for the streams, whereby to conduct each stream to the air-communiting zone or perforated area of the re-aerator; which zone is shown in Fig. 2, as an air-communiting annular zone, to which one said stream is 115 brought to the interior and the other,—preferably the air-stream,—is brought or guided to the exterior. Thus the two said streams 120 may be said to be re-combined into a newly formed compound stream having the air content thereof in a freshly comminuted form.

125 In said closed air-circuit system, (Fig. 1), air segregated from one position, as F^6 , is next utilized for aeration at a more advanced position in the circuit, but under a 130

higher pressure, this position being herein shown as the place of initial aeration of the upflowing column. Within the regenerator itself,—as shown in Fig. 2,—this sequential segregation and re-use of the air occurs in a more immediate manner, the re-use occurring at a position closely following the place of air-segregation, whereas in the apparatus of Fig. 1, these two successive positions, as F' and G' are much more remote from each other, but are in a single column and under the same submergence effect. However, as regards the segregation of the air at one position in the column and a subsequent re-use of the same air for aerating the liquid at another position in the same column, those two systems are deemed to be, broadly considered, similar in character and as to sequence utility.

Having thus described my invention, I claim:—

1. In a regenerator air-lift system, in combination, a liquid-uptake column; means for supplying air under greater than atmospheric pressure; means for conveying said air to the lower end of said column; and means arranged in said column for segregating air from liquid passing through the column and re-aerating the liquid with the segregated air; the last mentioned means comprising two adjacent channels each of which is substantially circumflex form when viewed in section, one channel being of uninterrupted flow and the other channel being of restricted flow for segregating the air in said liquid, and means arranged between the channels for passage of the segregated air from the flow restricting channel to the channel of uninterrupted flow for re-aerating the liquid therein.

2. In an air-circuit regenerator air-lift system, in combination, a liquid-uptake column; means for supplying air under greater than atmospheric pressure; means for conveying said air to the lower end of said column; means arranged in said column for segregating air from liquid passing through the column and re-aerating the liquid with the segregated air; means for segregating air from said liquid after air segregation and re-aeration of the liquid by said air segregating and re-aerating means; means for conveying to the air supplying means air segregated from the liquid by said air segregating means; and means for discharging the de-aerated liquid from the upper end of said column; said means for discharge being located at a higher level in said column than said air segregating means.

3. In an air-circuit regenerator air-lift system, in combination, a liquid-uptake column having sections; an air tank; and an air segregator having a casing comprising a liquid stream channel and an air segregation channel diverging from the stream

channel and communicating with the air tank; the air segregator being arranged in said column near the upper end thereof and providing means for maintaining section ends of the column in alignment with each other and said stream channel communicating with the discharge outlet of said column at the upper end of the column.

4. In a regenerator air-lift system, in combination, a liquid-uptake column; means for supplying air under greater than atmospheric pressure; means for conveying air to the lower end of said column; and regenerators for segregating the air from liquid passing through said column and re-aerating the liquid with the segregated air; each of said regenerators comprising a casing having therein two adjacent channels, one channel being of uninterrupted flow and the other channel being of restricted flow for segregating the air in said liquid, the channel of restricted flow at its upper end forming a chamber surrounding the upper end of the channel of uninterrupted flow, and air comminuting means arranged between said chamber and channel for passage from said chamber to said channel of air segregated from said liquid for re-aerating the liquid in said channel.

5. In a regenerator air-lift system, in combination, a liquid-uptake column having sections; means for supplying air under greater than atmospheric pressure; means for conveying said air to the lower end of said column; and regenerators for segregating air from liquid passing through the column and re-aerating the liquid with the segregated air; each of said regenerators comprising a casing having therein when viewed in section two adjacent channels of circumflex form, one channel being of uninterrupted flow and the other channel being of restricted flow for segregating the air in said liquid, the lower end of the channel of restricted flow being substantially co-axial with said column and the upper end of the channel of uninterrupted flow being substantially co-axial with said column, and air comminuting means arranged between the channels for passage of segregated air for re-aerating the liquid in the channel of uninterrupted flow; said casing providing means for maintaining column section ends in alignment with each other.

6. In a regenerator air-lift system, in combination, a liquid-uptake column having sections; means for supplying air under greater than atmospheric pressure; means for conveying said air to the lower end of said column; and regenerators for segregating air from liquid passing through said column and re-aerating the liquid with the segregated air; each of said regenerators comprising a casing having therein when viewed in section two adjacent channels of

circumflex form, one channel being of uninterrupted flow and the other channel being of restricted flow for segregating the air in said liquid, the lower end of the channel of restricted flow being substantially coaxial with said column and the upper end of the channel of uninterrupted flow being substantially co-axial with said column, the upper end of the channel of restricted flow providing a chamber surrounding the upper end of the channel of uninterrupted flow, and air comminuting means arranged between said chamber and the channel of uninterrupted flow for passage of segregated air for re-aerating the liquid in said channel; said casing providing means for maintaining column section ends in alinement with each other.

7. In an air-circuit regenerator air lift system comprising a liquid-uptake column having sections, an air segregator having a casing comprising a liquid stream channel and an air segregation channel diverging from the stream channel for passage of air therethrough; the air segregator being arranged in said column and providing means for maintaining section ends of the column in alinement and said stream channel communicating with a section end of said column.

8. In a regenerator air lift system having a liquid-uptake column, a regenerator for segregating the air from liquid passing through said column and re-aerating the liquid with the segregated air, said regenerator comprising a casing having therein two adjacent channels, one channel being of uninterrupted flow and the other channel being of restricted flow for segregating the air in said liquid, the channel of restricted flow at its upper end forming a chamber surrounding the channel of uninterrupted flow, and air comminuting means arranged between said chamber and channel for passage from said chamber to said channel of air segregated from said liquid for re-aerating the liquid in said channel.

9. In a regenerator air lift system having a liquid-uptake column, a regenerator for segregating air from liquid passing through said column and re-aerating the liquid with the segregated air, said regenerator comprising a casing having therein when viewed in section two adjacent channels of circumflex form, one channel being of uninterrupted flow and the other channel being of restricted flow for segregating the air in said liquid, the lower end of the channel of restricted flow being substantially co-axial with said column and the upper end of the channel of uninterrupted flow being substantially coaxial with said column, and air comminuting means arranged between the channels for passage of segregated air for re-aerating the liquid in the channel of uninterrupted flow.

10. In a regenerator air lift system having a liquid-uptake column, a regenerator for segregating air from liquid passing through said column and re-aerating the liquid with the segregated air, said regenerator comprising a casing having therein when viewed in section two adjacent channels of circumflex form, one channel being of uninterrupted flow and the other channel being of restricted flow for segregating the air in said liquid, the lower end of the channel of restricted flow being substantially co-axial with said column, the upper end of the channel of uninterrupted flow being substantially coaxial with said column, the upper end of the channel of restricted flow providing a chamber surrounding the upper end of the channel of uninterrupted flow, and air comminuting means arranged between said chamber and the channel of uninterrupted flow for passage of segregated air for re-aerating the liquid in said channel.
